David Wilkinson of Cohoes New York
Letters Patent

The Schedule is referred to in this Letter Patent and making part of the same containing a description in the words of the said David Wilkinson himself of his Improvement in the Canal Lock Gate.

Be it known that I David Wilkinson of the Town of Cohoes in the County of Albany and State of New York have made a new and useful improvement in Canal Lock Gates, called "Wilkinson's improved Lock Gate", which is described as follows, reference being had to the annexed drawings of the same making part of this Specification: A represents the frame of the Gate constructed in the usual manner, B. an eccentric lever, C. a moveable eccentric fulcrum, D. a movable part of the moveable eccentric fulcrum, turning on a fixed pivot, E. A circular plate set the end of the eccentric lever to which the arm B. and connecting rod F. are attached and which lever and pivot is mounted in the rim of the circular plate, the pin C being the moveable eccentric fulcrum before mentioned, H. Staples to keep the connecting rod and arm in their proper positions, I. hinge or joint in the connecting Rod, K. the valve, L. the axis on which the valve turns, M. semi-circular ends or flanges of the valve, N. pins by which the connecting Rod is attached to the rim of one of the semi-circular ends of the valve, O. being much better to make the attachment at the end instead of the centre of the valve on account of the liability by the latter mode of arresting the passage thro' the valve opening of Stay Straw Sticks &c; which may fall into the canal. O. bevelled or chamfered bottom of the valve opening against which the valve shall light. Operation. The axis of the valve being placed below the centre making the area of the upper part greater than that of the lower or concave, the pressure of the water will be greater upon the upper than upon the lower part and will therefore keep the valve light against the bevelled edge of the bottom. When it is required to open the valve, the power is applied to the end of the eccentric

lever and raised and made to perform a movement of a curved or elliptical which opens the valve by means of the connecting rod attached to a pin in the periphery of the semicircle of the valve and to a pin in the periphery of the circular plate of the valve. The power of the movement is greatest on a maximum, the fulcrum being then the shortest, and when the lever is at an angle of 90° with the fore-
ground or parallel with the connecting rod the power is least or a
minimum, but at the same time it is a maximum on the diameter
of the valve, the lever being then the longest. This combination of
the lever for opening and shutting the valve of a canal-lock-gate is
very simple, strong, and easily managed by any person of the com-
munity as may be seen by examining the annexed drawings.

In a slide valve it will be necessary to move the lever half a
circle to prevent the valve falling back when the water is down and
the pressure off. What I claim as my invention and never
before known is the application of the before described eccentric lever
with the suitable connections to gain power and lose velocity, or vice
velocity and gain power, as may be required for opening and shutting
the valves of canal-lock-gates in the manner herein before described.
The dimensions and materials have not been mentioned as these are
the arrangement of the parts may be varied in any manner to suit the
views of the constructor; abiding however by the principle of the inven-
tion as, before laid down.
